SCREEN CENTRIFUGE FOR
CLEANING CLAYS

Karl Ludwig Gerecht, Kassel, Germany

Application July 27, 1951, Serial No. 238,910
In Germany December 30, 1948

12 Claims. (Cl. 209—279)

1

This invention relates to a centrifuge for cleaning the raw material for brick works and the like.

For making ordinary ceramic ware of loam, clay, or the like, such as, e. g., in brick works, it is necessary as much as possible to remove the mechanical impurities from the raw material. The disturbing admixtures are on the one hand remnants of plants, roots etc. and, on the other hand, stony admixtures, more particularly, limestone.

The machines hitherto used for removing such impurities are very complicated and expensive. Moreover, ordinarily several machines have to be arranged in series. Thus, for instance, a coarse disintegration takes place in the edge mill from which the mass comes to a finishing rolling mill for crushing all stones etc. to a size of 1 mm. diameter in maximum. Especially the finishing mill is very highly stressed, and the hard steel rollers have to be reground very often.

It is an object of the present invention to provide a machine avoiding such disintegrating processes which would involve heavy wear and tear of the disintegrating machines.

Another object of the invention is to free the raw material for ordinary ceramic ware from the mechanical impurities, such as, stones, roots, remnants of plants, etc. by means of centrifugal force, and to carry out this cleaning continuously.

Still another object of the invention is to free the raw material from all impurities whose dimensions exceed a certain minimum size, e. g., 1 to 3 mms., because these impurities primarily include limestone which in the finished product may cause disturbances, e. g., scaling of parts of the product.

Still a further object of the invention is to provide a centrifugal separating apparatus which is of simple construction, easy to clean, and adapted to the rough working conditions prevailing in brick works.

With these and further objects in view, the present invention relates to a centrifugal separator in which a plurality of screening baskets are concentrically arranged around a vertical shaft, in such a way that the size of the screen openings decreases from the innermost towards the outermost basket, while the outermost screening basket is encompassed by a stationary wall adapted to receive or collect the purified clay. The sieves may consist, for instance, of perforated plates, the diameter of the perforations being larger in the innermost basket than in the next larger basket, in order to retain the differ-

ent impurities in the different sieves in a fractionated form. It is important that the last or outermost screening basket has openings whose diameter amounts to a few millimeters only, e. g., about 1 to 3 mms.

Preferably the screening baskets consist of grates which may be formed of wires, bars or the like, and the width of the gaps of the grates decreases from the innermost to the outermost basket.

The clay or similar material is fed, advantageously in a soaked condition, from a stage arranged above the separator, near its axis. The clay substance travels successively through the different grates by which the impurities are retained in different fractions. Preferably some of the grate baskets are conically shaped and alternately tapered in an upper and lower direction, so that the impurities separated therein are discharged, under action of the centrifugal forces, partly in a downward and partly in an upward direction.

A horizontal disc may be mounted on the centrifugal shaft, below the grate baskets, for collecting and removing the coarse stones which are imparted a considerable centrifugal acceleration, so that they will freely flow out of the operating range of the centrifuge, through the clay slipping down from the stationary collecting wall.

In order that the raw material fed in the central part is immediately imparted the desired peripheral speed, it is advantageous to provide means in the inner basket for setting the mass in rotation. To this end, e. g., vanes or blades may be provided on the shaft in a substantially vertical direction. In addition to, or instead of, the vanes, horizontal baffle plates may also be provided. Preferably these vanes are forwardly inclined in their upper part, in the direction of rotation, e. g., they may form an angle of about 45° with the vertical plane of the lower vane part.

It has been found that in operating the centrifuge an intensive outwardly directed air current is produced. It is preferred to direct this air current in such a way that air eddies are prevented but that the air current promotes the separating process and the slipping down of the clay from the clay collecting wall. This effect is obtained by the provision of fan like vanes at the centrifugal basket, e. g., by the above mentioned use of bent-off blades in the innermost screening basket. Moreover, it is preferred to provide vanes also between the screening baskets, which vanes likewise are forwardly inclined in the direction of rotation, throughout their length,

or in the upper part, in order to produce a downwardly directed air current during the rotation of the centrifuge. Moreover, the centrifugal basket may have vanes at its outer periphery to the same end, which vanes may be forwardly inclined entirely or partly, in the direction of rotation.

It has been found that in general it will be sufficient to provide two screening baskets or grate baskets, the interior of which, for instance, has slits of a few centimeters, e. g., 3 cms., but not more than 5 cms., while the outer basket has a slit width of a few millimeters, at least about 1 mm. and not more than about 3 to 4 mms.; preferably the slit width in this case is 2.5 mms.

In order to facilitate the slipping down of the impurities retained at the screens or grates, the grates may have an inclined cross section, i. e., the baskets may be conically shaped. In this case it is advantageous to construct the inner basket in such a way that it is conically tapered in an upward direction, while the outer basket is conically tapered in a downward direction. The coarse impurities, e. g., stones, are thus passed downwards, falling onto a disc mounted on the centrifugal shaft, from which they are centrifuged outwards, outside the reach of the centrifuge. The finer impurities, e. g., small particles of limestone, are retained at the outer grate basket, slipping outwards over the upper edge thereof. The entire centrifuge may be encompassed by a collecting wall or a casing by which the fractions of the impurities discharged by the two baskets are collected.

The purified or cleaned clay slips downwards on the stationary clay collecting wall surrounding the outer screening basket, falling into a funnel provided underneath the centrifuge, from which funnel it may be delivered, through conveyor belts, conveyor worms, elevators or the like, to the subsequent processing plants. It is also possible, however, to transport the purified clay by means of wheel-barrows, conveyor wagons or the like.

It will thus be seen that the whole cleaning of the clay or loam is achieved by means of a single machine comprising a multiple centrifuging basket, a clay-collecting wall, a funnel for delivering the clay and a casing for collecting the impurities separated by centrifuging. Advantageously the centrifuge is suspended like a pendulum and the driving motor is provided directly on the upper end of the shaft of the centrifuge on a stage from which the raw material is fed to the centrifuge continuously or discontinuously.

Other and further objects, features and advantages of the invention will be pointed out hereinafter and appear in the appended claims forming part of the application.

In the accompanying drawings a now preferred embodiment of the invention is shown by way of illustration and not by way of limitation.

Fig. 1 is an axial section through the separator,
Fig. 2 is a section on line II-II of Fig. 1,

Fig. 3 is an elevation of the separator, a part of the outer wall being removed,

Fig. 4 is a fragmentary section, on a larger scale,

Fig. 5 is a development showing the arrangement of the vanes.

Referring now to the drawings in greater detail, in which similar reference numerals denote similar parts, it will be seen that a supporting structure for the separator, comprising girders

1, 1', and 1'' of steel, reinforced concrete, wood or the like bears girders 2 and 3 on which the driving motor 4 with the rotary part of the separator and the stationary casing is mounted.

5 The lower bearing 5 of the driving motor 4 is reinforced to resist the heavy loads bearing thereon. A braking device 6, adapted to be operated by a hand lever 7, permits quick braking of the centrifuge which is driven at a suitable rate of speed, e. g., of about 960 R. P. M.

10 The rotary part of the centrifuge is secured on the shaft 8 with a conical seat. The carrier body 9 bears the screening means and comprises a hub 10 and an angular ring 11 which parts are interconnected by six ribs 12 in such a way that hollow spaces for passage of the large stones are left.

15 A ring plate 13 secured on the carrier 9 bears the inner screening basket with the sieving bars 14 which are held in three rings 15, 15' and 15'' of section steel as shown. The inner screening basket is conically tapered from bottom to top. Mounted within this basket, on the shaft 8, are vertical vanes 16 whose upper part 16' is bent off at an angle of 45°.

20 The outer screening basket is built up of rings with angle irons 17 and 17'. The angle irons serve to fasten the tentering frame for the wires. The upper and lower rings of the tentering frame are interconnected by inclined bars 18 bearing one or two rows of perforations for the reception of steel wires 19 which are drawn in under tension in a peripheral direction, thus forming a sieve. By way of alternative it is also possible to use annular slit sieves of metal or the like. The upper ring for the angle irons 17' is carried by round iron bars 20. Moreover, flat iron bars 21 are arranged between the upper ring with the angle iron 17' for holding the sieving frame and the outer edge of the centrifuge disc 13, Fig. 3, in such a manner that said flat iron bars are directed from one round iron support 20 to the next, forming an angle of about 45°. This inclination serves to produce an air current in a downward direction, whose intensity is further reinforced by inwardly directed plate or sheet members 22 provided on the flat iron bars 21.

25 Provided in the space between the inner and outer screening baskets are vertical plate members 23, Figs. 4 and 5, whose upper part is bent off at an angle of about 45°. These plate members 23 are fastened on a frame of steel bars formed by the horizontal bars 24, 25, 26 and the vertical bar 27. In their upper part projecting over the outer screening basket the inclined plate members 23 are outwardly extended, the extensions 23' also being downwardly enlarged. A reinforcing bar 28 serves to support the enlarged part 23' of the plate member.

30 The spaces between the bars 14 are adapted in such a way that stones of a diameter of 2 cms. and more are retained by them, while the mesh width of the screen wires 19 does not exceed 1 to 2.5 mms., depending on the conditions of the raw material.

35 Mounted on the shaft 8, below the grate baskets, is the collecting plate 29 with a suitable space for discharging the stones retained by the grate 14 and falling down onto plate 29.

40 The rotary centrifuge is enclosed in a stationary casing 31 bearing on the frame 2 by means of an angle iron ring 30, and consisting of a cylindrical outer jacket 31 and a closure ring 32 on which is secured a covering plate 33 45 provided with a circular aperture 34 for feeding

5

the raw clay to be treated. Secured to the sheet iron cover 31 by means of screws 35 and spacing sleeves 36 is the clay collecting plate 37 whose upper part 38 is inwardly contracted.

Provided in the downward extension of the clay collecting plate 37 is the clay collecting funnel 39 serving to collect the clay slipping off from the clay collecting plate 37. Suspended on pivots 41 at the lower edge of the collecting plate 37 are sheet metal strips 49 which in their vertical position substantially cover the space between the sheet member 37 and the funnel 39.

The operation of the apparatus is as follows: The raw clay entered through the feed hole 34 is seized in the innermost sieving chamber by the blades or vanes 16 driven by the motor 4 through the shaft 8 and centrifuged against the sieve 14 by which the coarse stones of a size of more than 2 cms. are retained and guided downwards, under centrifugal and gravity action, until they fall onto the disc 29 by which they are centrifuged beyond the reach of the funnel 39. The clay thus preliminarily purified enters into the central sieving space where the impurities e. g. above 1 mm. or up to 2, 5 mms., are retained by the screen wires 19. On its passage through this screen the clay is homogenized and worked through, whereby aging of the clay is superseded, more particularly, if the amount of water contained in the clay is properly adjusted. The small limestones retained by this sieve will travel upwards, where they are discharged over the upper edge of the sieve, under centrifugal action. It may be that some of them are caught in the wires; however, their quantity is so small that it is sufficient to have this screen cleaned once a day after the working period. The clay discharged from the centrifuge is deflected by the collecting wall 37 towards the funnel 39 from which it is carried off by means of wagons, conveyer belts, or conveyer worms.

In order to prevent the clay from sticking in the narrow slits of the sieve 19 it is necessary to have additional air pressure act upon the sieve. This air pressure is produced by the vertical plates 23. Owing to the fact that the upper portion of the plates 23 is bent at an angle of 45°, the air pressure is uniformly distributed in the spaces between the plates and the air is preventing from escaping in an upward direction.

In order to permit the air current to be efficiently discharged in a downward direction and to prevent the particles of clay from sticking at the clay collecting wall 37, blast deflector plates 21 are provided, with their extension 22 behind the screen 19, at an angle of 45°.

In order to prevent the mixing of clay and separated stones in the interspace provided for centrifuging the larger stones between the clay collecting wall 37 and the funnel 39, it is necessary to produce a downward air draft also in the space between the clay collecting wall 37 and the outer casing 31, which draft is produced by the enlarged upper portions of the plates 23. The subsequent mixing of clay and smaller stones can also be prevented by strip-shaped sheet members suspended on the outer side of the clay collecting wall in such a way that their lower ends are outwardly moved by emitted stones only and will fall back to the border of the funnel by their own gravity.

The output of the separator may be adapted to the actual working conditions. It is determined primarily by the construction of the outer grate. In a separator having a grate passage

6

area of about 0.4 m.² the output is higher than that of any conventional brick press or brick moulding machine.

While the invention has been described in detail with respect to a now preferred example and embodiment of the invention it will be understood by those skilled in the art after understanding the invention that various changes and modifications may be made without departing from the spirit and scope of the invention and it is intended, therefore, to cover all such changes and modifications in the appended claims.

What is claimed is:

- 15 1. A centrifugal separator for the cleaning of raw material for ordinary ceramic ware, comprising a vertical rotary shaft, two sieving baskets concentrically arranged on said shaft, the outer basket having a smaller mesh width than the inner basket which is upwardly tapered, a collecting wall for the cleaned raw material surrounding the outer basket, and a horizontal disc mounted on the shaft below said baskets, for discharging the coarse impurities.
- 20 2. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and substantially vertically arranged vanes within the inner basket.
- 25 3. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and substantially vertically arranged vanes within the inner basket, the upper part of said vanes being forwardly inclined in the direction of rotation.
- 30 4. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets.
- 35 5. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and outward direction.
- 40 6. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 45 7. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 50 8. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 55 9. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 60 10. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 65 11. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 70 12. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and
- 75 13. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and

outward direction, the upper part of said vanes being forwardly inclined in the direction of rotation.

7. A centrifugal separator for purifying the raw material for ordinary ceramic products, comprising a vertical rotary shaft, two sieving baskets concentrically mounted on said shaft, the outer basket having smaller sieving openings than the inner basket, a stationary collecting wall for the purified raw material encompassing the outer basket, and vanes substantially vertically arranged between the two baskets and projecting over the outer basket in an upward and outward direction, each vane being stiffened in at least one of the horizontal and vertical directions.

8. In a centrifugal separator for purifying the raw material for ordinary ceramic products, a vertical rotary shaft, two sieving baskets, concentrically mounted on, for rotation with, said shaft, a collecting wall for the purified raw material surrounding the outer basket, a disk rigidly connected to the shaft and carrying the baskets, the upper rim of the outer basket being supported on said disk thus forming a supporting structure together therewith, and vanes forwardly inclined in the direction of rotation, within this supporting structure.

9. In a centrifugal separator for purifying the raw material for ordinary ceramic products, a vertical rotary shaft, two sieving baskets, concentrically mounted on, for rotation with, said shaft, a collecting wall for the purified raw material surrounding the outer basket, a disk rigidly connected to the shaft and carrying the baskets, the upper rim of the outer basket being supported on said disk thus forming a supporting structure together therewith, and vanes forwardly inclined in the direction of rotation, within this supporting structure, said vanes extending inwardly up to the outer basket.

10. A centrifugal separator for the cleaning of raw material for ordinary ceramic ware, com-

prising a vertical rotary shaft, two sieving baskets concentrically arranged on said shaft, the outer basket having a smaller mesh width than the inner basket, a collecting wall for the cleaned raw material surrounding the outer basket, a stationary discharge funnel arranged below the sieving baskets, said funnel having an upper diameter approximately equalizing that of the collecting wall, and plates pivotally suspended from the lower edge of the collecting wall and substantially covering the vertical interspace between the collecting wall and the discharge funnel.

5 11. A centrifugal separator for the cleaning of raw material for ordinary ceramic ware, comprising a vertical rotary shaft, two sieving baskets concentrically arranged on said shaft, the outer basket having a smaller mesh width than the inner basket, a collecting wall for the cleaned raw material surrounding the outer basket, a stationary discharge funnel arranged below the sieving baskets, said funnel having an upper edge with a diameter approximately equaling that of the collecting wall, the upper edge of said funnel being spaced from the lower edge of said wall to 15 form an opening, and plate means secured to said shaft for the discharge of coarse impurities from said separator through said opening.

20 12. A centrifugal separator as in claim 11, further comprising said inner basket having a downward outwardly tapering wall, and said outer basket having an upwardly outwardly tapering wall.

KARL LUDWIG GERECHT.
